UNITED STATES PATENT OFFICE.

JAMES R. CRUIKSHANK, OF VANCOUVER, BRITISH COLUMBIA, CANADA.

ROTARY TOOTHBRUSH.

Application filed April 15, 1922. Serial No. 553,067.

To all whom it may concern:

Be it known that I, JAMES R. CRUIKSHANK, a subject of the King of Great Britain, residing at the city of Vancouver, in the Province of British Columbia, Canada, have invented certain new and useful Improvements in Rotary Toothbrushes, of which the following is a specification.

My invention relates to improvements in rotary tooth brushes, and the object of my invention is to provide a device of this nature in which the brush member is adapted to be revolved against the teeth by manually operated mechanism to brush the same by rotary movements instead of lateral movements, as is the prevailing, and inefficient, practice at the present time, and which device is simple in construction and operation and capable of being manufactured for sale and use in a highly convenient and attractive form.

I attain this object by the construction illustrated in the accompanying drawings in which—

25 Fig. 1 is an outside view of my tooth brush.

Fig. 2 is an outside view of Fig. 1 showing the cap removed and the operating handle at the end of the outstroke.

30 Fig. 3 is a longitudinal sectional view taken on the centre line of Fig. 2.

Fig. 4 is a detail view of one form of the rotary brush member.

Fig. 5 is a detail view of an alternative 35 form of the rotary brush member.

Fig. 6 is a detail view of a brush member for lateral movement.

Fig. 7 is an end view of Fig. 2.

Fig. 8 is a side view of a celluloid capsule 40 containing a brush member.

Fig. 9 is a detail view in perspective, of the nuts and engaging bar.

Similar numerals of reference indicate similar parts throughout the several views.

45 The device consists of a socketed member 1 rotatably mounted in a sleeve 2 having in one end the socket 3 and connected at its other end to the end of a right and left spirally grooved rod 4 longitudinally movable

50 within a cylindrical sleeve or handle 5, on which rod and within the sleeve are mounted nuts 6 and 7, one nut co-operating with the right hand spiral groove and the other nut with the left hand one. 8 indicates a button member slidably in a slot 9 formed in the sleeve adapted to move into or

out of engagement with one or other of the nuts a short bar 10 according as the button is moved to either end of the slot, the nuts having peripheral notches or slots co-operating with the bar so that when the bar is engaged with a slot of nut 6 this nut is held to the sleeve 5 while nut 7 is free of the sleeve and when the bar is engaged with a slot of the nut 7 this nut is held to the sleeve 5 while nut 6 is free of it. If therefore the right hand nut is held to the sleeve and the sleeve, that is, the handle 5, moved forward towards the socketed member 1 the rod 4 will rotate in a left hand direction the 70 left hand nut running free while if the left hand nut be connected to the sleeve the rod will rotate to the right.

The construction described in the foregoing is well known, as also is its operation, 75 and therefore it is thought requires no further description.

Mounted on the inner end of the grooved rod 4 is a washer 11 fitting slidably the bore of the handle 5 and between the washer and the end of the handle, which is closed, is a spring 12 which, when the pressure on the handle is relieved at the end of the inward stroke, returns it to the normal position.

The brush member consists of a short 85 stem or shaft 13, of any suitable material such as bone, the inner end of which is adapted to fit tightly in the socket 3 when pushed therein under hand pressure while its outer end is provided with suitable bristles 14 arranged circularly round the stem, the preferred arrangement being a cylindrical brush 15 the periphery of which is concave to suit the shape of the teeth and there may be one or more such brushes mounted 95 on the stem, there being two shown in the drawing, Figs. 1 to 4. An alternative form of brush member may be used, as shown in Fig. 5, in which the brush consists of a series of circular brushes 16 arranged side 100 by side on the stem, while if desired a stem provided with the form of brush in present use for lateral movements, as at 17 in Fig. 6, may be used.

18 indicates a guard secured to the sleeve 105 2 to keep the brush clear of the mouth wall while rotating, and 19 indicates a cap adapted to cover the brush when not in use, which cap may be provided with a clip 20 so that the brush may be carried in the vest or 110 jacket pocket.

In use the cap 19 is removed and the brush

held against the teeth, the sleeve 2 being held by the fingers of one hand, whereupon the brush may then be rotated by gripping the handle 5 by the fingers of the other hand 5 and moving the handle back and forth laterally as long as is required. Should it be desired to brush the teeth laterally the rotary brush member is removed from the socket and the brush 17 is inserted in its 10 place, when the brush may be used like an ordinary toothbrush.

From the foregoing it will be seen that I have devised a simple tooth brush capable of being used at will either as a rotary brush 15 or for lateral movement, which is handy and convenient, and which enables the alternative forms of brush members to be carried in capsule form in a readily portable manner for immediate use, as shown at 23 in 20 Fig. 8.

What I claim as my invention is:—

A rotary tooth brush comprising, in combination, a stationary sleeve, a socketed member rotatably mounted in said sleeve, a spirally grooved rod to the outer end of 25 which said socketed member is secured, a cylindrical handle within which the inner end of the rod extends, a nut rotatably mounted on said rod within the handle grooved correspondingly to the rod groove, 30 means for detachably connecting the nut to the handle whereby lateral movement of the handle causes rotation of the rod, and a stem removably mounted in the socket of the socketed member provided at its free 35 end with a rotary brush.

In testimony whereof I affix my signature at Vancouver, B. C., this 7th day of April, 1922.

JAMES R. CRUIKSHANK.
